UNITED STATES PATENT OFFICE.

LAMAR H. SHOVER, OF MILWAUKEE, WISCONSIN, ASSIGNOR TO PANAY HORIZONTAL SHOW JAR CO., OF MILWAUKEE, WISCONSIN, A CORPORATION OF WISCONSIN.

DESIGN FOR A DISPLAY DEVICE.

Application filed November 4, 1921. Serial No. 512,911. Term of patent 3½ years.

To all whom it may concern:

Be it known that I, LAMAR H. SHOVER, a citizen of the United States, residing at Milwaukee, in the county of Milwaukee and State of Wisconsin, have invented a new, original, and ornamental Design for Display Devices, of which the following is a specification, reference being had to the accompanying drawing, forming part thereof.

The figure is a perspective view of a display device showing my new design.

I claim:

The ornamental design for a display device as shown.

LAMAR H. SHOVER.
